UNITED STATES PATENT OFFICE

THOMAS I. POTTER, OF PORTLAND, OREGON

PUMP FOR REFRIGERATING MACHINES

Application filed November 4, 1929. Serial No. 404,586.

This invention relates generally to the art of mechanical refrigeration, and particularly to a refrigerating machine having a novel form of compressor and oil separating system.

The main object of this invention is to provide a refrigerating machine especially adapted for small installations, which will be easy to manufacture and which will require only the minimum amount of attention in the way of service.

The second object is to provide a refrigerating machine which will be exceedingly quiet in operation and the use of which will not be accompanied by the objectionable escape of refrigerants.

The third object is to provide a refrigerating machine having an improved form of compressor the parts of which are at all times completely lubricated and made easily accessible, and also to include in said compressor a special form of oil separator by means of which the lubricant is removed from the refrigerant before same passes through the system.

The fourth object is to provide a special form of evaporator box which will provide automatic defrosting thereof.

These, and other objects, will become more apparent from the specification following as illustrated in the accompanying drawings, in which:

Figure 1 is a plan view of the machine showing the separator cut away in a horizontal section.

Figure 2 is an elevation of the machine showing its connections to a refrigerating compartment.

Figure 3 is an end elevation of the compressor showing parts broken away in section.

Figure 4 is a vertical section through the compressor taken along the line 4-4 in Figure 2.

Figure 5 is a section through the compressor taken along the line 5-5 in Figure 2.

Figure 6 is a section taken along the line 6-6 in Figure 4.

Figure 7 is a section taken along the line 7-7 in Figure 4.

Figure 8 is an enlarged fragmentary section through the packing gland.

Similar numbers of reference refer to similar parts throughout the several views.

Referring in detail to the drawings, there is illustrated a compressor consisting of a base 10 on which is mounted a cylinder housing 11 which is secured to the base 10 by means of the bolts 12. The sides 13 of the cylinder housing 11 extend upwardly to form a crank case preferably provided with the fins 14 for the radiation of heat. One side 15 of the crank case is closed and has formed therein a pair of bearings 16 and 17 preferably provided with bushings 18 in which journals an eccentric shaft 19 on whose inner end is formed the eccentric 20 and on whose reduced end 21 is mounted a fly wheel belt pulley 22. The belt line of the pulley 22 is preferably as close as possible to the outer bearing to avoid over-hang.

Around the loose end 21 is placed the gland bushing 23 provided with a shoulder 24 adapted to engage a rubber gasket 25 in the recess 26 of a cap 27. There is a large clearance between the shaft portion 21 and the interior of the bushing 23, and a corresponding clearance between the exterior of the bushing 23 and the recess 26. The end 28 of the bushing 23 is provided with a seat which engages the shouldered end 29 of the shaft 19. The clearances referred to make it possible for the bushing 23 to float upon the rubber gasket 25 and thereby provide a perfect seal for the compressor.

Within the cylinder housing 11 is formed a cylindrical bearing surface 30 in which is mounted a cylinder body 31 having a bore 32 formed across the diameter thereof entirely through same. Through the bottom of the housing 11 are formed the curved inlet and outlet ports 33 and 34 which communicate with the lateral passageways 35 and 36. The base 10 serves as a cover plate for the lower ends of the ports 33 and 34, and in some instances the base 10 is made integral with the housing 11.

On the eccentric 20 is mounted an eccentric strap 37 which forms a part of the piston 38 mounted in the bore 32. On each side of

the cylinder body 31 is formed a hub 39. On opposite sides of the cylinder body 31 are disposed the projection 40 which forms a part of the side 15, and the projection 41 which forms a part of the side 42 which really constitutes a cover plate for the compressor and is removably secured thereon by means of the bolts 43. There is considerable clearance on each side of the hubs 39 to prevent the cylinder body 31 from being bound between the projections 40 and 41.

10 Mounted in the cover 42 is a ball 44 which is urged toward the eccentric 20 by means of a spring 45 which reacts between the member 42 and a cup 46 which is slidably mounted in the member 42. The ball 44 engages a hardened plug 47 in the end of the eccentric shaft 19. The function of the spring 45 is to hold the faces 28 and 29 to a seat at all times.

15 Forming a part of the cover plate 42 and at the top end thereof is an oil separator 48 in, the bottom of which is mounted a gas equalizing pipe 49 which communicates with the interior of the compressor and extends almost to the top of the oil separator 48. At 20 one corner of the oil separator and at the upper portion thereof is formed a bottomless walled compartment 50 from which warm compressed refrigerant can flow through the pipe 51 to a condensing coil 52 which may be cooled by the fan 53 on the shaft 54 of the motor 55 which is, in turn, mounted on an elevated base 56 which rises above the main base 57 on which is also mounted the base 10 of the compressor. On the shaft 54 is also placed a pulley 58 whose belt 59 drives the pulley 22. Obviously, heat may be drawn from the coil 52 in any other convenient manner.

25 Underneath the elevated base 56 is placed a receiver 60 to which liquefied cooled refrigerant passes from the coil 52 by means of the pipe 61. From the receiver 60 the refrigerant flows through the pipe 62 to an expansion valve 63, which may be of any type suitable for the purpose. From the expansion valve 63 the refrigerant is permitted to expand into the expansion coils 64, which coils are wound on a cast expansion box 65 30 preferably provided with grooves for the reception of the tubing for the purpose of providing a better contact between the tubing and the metal in the box, and also to prevent frost from forming an insulation which will 35 retard the flow of heat from the interior of the box to the interior of the coil 64.

40 The relation of the mass of metal in the box 65 and the refrigerating capacity of the machine, and also to the loss of heat by leakage in the refrigerating compartment itself, is such as to provide automatic defrosting of the expansion coils 64 during the interval in which heat-pumping is stopped by means of the thermostat 66 mounted at approximately the middle of the height of the refrigerating

45 compartment 67, which thermostat controls the operation of the motor 55. Said defrosting takes place before the ice cubes which have been formed in the trays 68 begin to melt. In other words, there is a definite lag or retarding of the flow of heat between the food 69 and the ice in the trays 68. If there is a deficiency in this lag, automatic defrosting will occur, but the ice will melt each time the motor 55 is shut down, due to a minimum 50 temperature of the compartment 67, and if the lag is too great—that is if too much metal or heat-storing material is interposed between the food 69 and the ice—then defrosting will not occur unless the door of the compartment 67 is open.

55 From the expansion coil 64 the warm gaseous refrigerant returns by way of the pipe 70 to the intake port 33 of the compressor where it is compressed through the operation of the piston 38, which alternately covers and uncovers the ports 33 and 34 and discharged through the port 34, and through the pipe 71 enters the upper portion of the oil separator 48. Between the bottom of the oil separator 48 and the lowermost point of the compressor casing is formed a connecting passage 72 by means of which oil can flow to the bottom of the compressor without any liability of its becoming broken up into spray and possibly carried over to the condenser.

60 In the above described apparatus the separation of lubricant and refrigerant is complete.

65 It will be noted in Figure 7 that the intake and exhaust ports 33 and 34 are curved, the curvature of the inner side of each port conforming to the exterior of the piston. The purpose of this formation is to secure a relatively quick opening and closing of the ports 70 without any objectionable retarding of such opening and closing as would be occasioned if the piston was round and the port face was straight. It can also be seen that by this arrangement the working parts of the cylinder 75 are at all times perfectly lubricated and the cylinder body 31 is held to its seat at all times by the pressure within the crank case added to the weight of the body 31.

80 Between the bearings 16 and 17 is formed an elevated oil reservoir 73 which is kept full by splash from the moving parts.

85 It will be noted in Figure 6 wherein the eccentric is on a dead center that the outlet port 34 is somewhat nearer the bore 32 than is the inlet port 33, for the simple reason that during the operation of the compressor a certain amount of lap is necessary and if this should exist on the exhaust side then the compressor would be apt to pound, due to the trapping of liquids on the compression stroke; whereas a considerable lap on the intake side would not be objectionable since it would merely result in a creation of a partial 90 vacuum for a short space of time.

I claim:

1. In a refrigerating machine the combination of a compressor, an oil separator mounted at the top thereof, a conduit extending from the oil separator to the bottom of the crank case of the compressor, an equalizing pipe extending from the top of the crank case to the top of the separator, and a bottomless compartment formed at the top of said separator in which freed refrigerant can be collected and withdrawn for condensation purposes.

2. A compressor for refrigerating machines consisting of a cylinder housing, a crank case extending above the top of said housing, and also including one side of said crank case, a pair of bearings supported by said crank case side, an eccentric shaft journaling in said bearings, the inner end of said eccentric shaft having an eccentric thereon, an oscillating cylinder body mounted in said cylinder housing having a bore extending diametrically therethrough, said cylinder housing having a pair of ports formed therein adapted to engage opposite sides of said cylinder body bore at its extremes of oscillation, a piston in said cylinder body having a strap at its upper end encircling said eccentric, a cover plate for said crank case, an end thrust stuffing box on the outer end of said eccentric shaft, and a spring between said eccentric and said cover plate for maintaining a seal in said stuffing box.

3. In a compressor, the combination of a somewhat oval crank case having its smaller end lowermost and containing a journal for an oscillating cylinder body, a closure for one side of said crank case forming a part thereof, an eccentric shaft mounted in said closure having an oil well formed around the middle portion thereof, an eccentric on the inner end of said shaft, an oscillating cylinder body and piston operated by said eccentric, said eccentric shaft having a shouldered outer end, a packing gland encircling said reduced end and spaced therefrom but contacting at one end with said shaft shoulder, a resilient packing between said gland and its surrounding closure structure, said gland floating between said resilient gland and said reduced shaft portion, and a spring for urging said eccentric shaft shoulder to seat with said gland.

4. In a compressor, the combination of a crank case, a compression cylinder at the lower end thereof and an operating eccentric in the upper portion thereof, an oil separator mounted above the top of said crank case, an oil return duct communicating between the bottom of said separator and the bottom of said crank case, a pressure balancing duct communicating between the top of said crank case and the top of said separator, and a bottomless compartment within said separator whose lowermost portion lies between said

oil outlet and the top of said balancing duct, from which compartment the compressed refrigerant freed from lubricant can be drawn.

5. A compressor consisting of an oscillating pumping element having its cylinder lowermost and having its operating shaft uppermost and its cylinder bore extending entirely through its cylinder body, a journal for said cylinder body having curved ports formed therein providing an excess of lap on the intake side, an elevated oil separating compartment incorporated in said pumping element wherein compressed refrigerant may be delivered and wherein any oil which has been carried over from said compressor may be precipitated and wherein said precipitated oil may be returned to the bottom of the compressor, the bottom of said compressor constituting an oil reservoir, a pressure equalizing pipe communicating between the upper portion of said oil separating compartment and the upper portion of said compressor, and a collector for refrigerant which has been freed from lubricant having its intake between the top of said equalizing pipe and the bottom of said oil separating compartment.
